Iron Works, Inc., Dayton, Ohio, a corporation
of New York

Application May 17, 1934, Serial No. 726,030

17 Claims. (Cl. 178—25)

This invention relates to the printing or impressing of letters or other characters, and more particularly to printing telegraphs, and the like, having provision for controlling the imprinting 5 of characters at a remote point.

Printing telegraph systems are now widely used as for the transmission of press dispatches and the like, and in accordance with present practice such systems comprise a transmitting device electrically interconnected with receiving devices at 10 a number of receiving stations so that matter typed at the transmitter is reproduced on the several receiving machines. These printing telegraph systems, like the conventional typewriter, afford but a single value of letter space so that the 15 copy produced thereon is arranged as lines of random length in which only one margin may be aligned. That is, as in ordinary typewriting, the left hand margin of a sheet may be readily aligned 20 as by the provision of a suitable stop, but as the character spaces are of only one length and as the lines can only be properly terminated at the end of a word or at a place where a word may be properly hyphenated, the lines are necessarily of 25 random length so that a non-uniform right hand margin results. Such copy, having a ragged or non-uniform right hand margin, may serve adequately as a means of communication, but before such copy can be used in a newspaper column 30 or as a printed page it must be rewritten and rearranged in order that the lines may be made of uniform length or, in other words, in order that the lines may be justified.

Through the practice of this invention it is possible 35 to operate a printing telegraph machine in a manner that the transmitted copy is produced in lines of uniform length. Mechanism is incorporated in the machines whereby the character space length may be varied to afford a 40 spacing such that all lines are produced to a predetermined or justified line length. Such operation affords great advantages in that, for example, the justified copy taken directly from the machine may be converted, as by a photo- 45 lithographic process, or by photo-engraving, directly into a suitable printing form having justified lines as for use in a news column or a printed page.

It is therefore one of the principal objects of 50 this invention to provide printing telegraph apparatus controlled from the sending station for varying the spacing of the characters at the receiving station so that the characters may be associated in lines justified to a predetermined 55 length.

Another object of the invention is the provision of printing telegraph apparatus embodying a transmitter for selecting type characters and a receiver for associating the selected characters in spaced relationship, control mechanism being provided for operation at the transmitter to establish a value of character spacing at the receiver that is coordinated with the number of characters in a line of copy for reproduction of that line to a predetermined length. 5

Another object of the invention is the provision of printing telegraph apparatus having provision for the production of justified lines, and having a simple control therefor including an actuating key that is adapted for successive or repeat operation such that upon each actuation the character spacing is altered by the amount of one whole character space in the justified line length. 10 15

Other objects and advantages of the invention will be apparent from the following description, 20 the appended claims and the accompanying drawings.

In the drawings, which illustrate a preferred embodiment of the invention,—

Fig. 1 is a side elevational view of a printing 25 telegraph transmitting machine constructed in accordance with this invention;

Fig. 2 is an elevational view of a portion of the machine shown in Fig. 1; the view being taken as indicated by the line 2—2 of Fig. 1; 30

Fig. 3 is a fragmentary plan view of the justifying device, with some of the parts removed for clearness of illustration;

Fig. 4 is a vertical sectional view taken on the line 4—4 of Fig. 3; 35

Fig. 5 is a fragmentary elevational view of the escapement mechanism at the transmitting machine;

Fig. 6 is a fragmentary sectional view taken on the line 6—6 of Fig. 3; 40

Fig. 7 is a fragmentary sectional view taken on the line 7—7 of Fig. 3;

Fig. 8 is a fragmentary elevational view of a portion of the space adjusting mechanism;

Fig. 9 is a fragmentary elevational view, partly 45 in section, of one of the control keys at the sending station;

Fig. 10 is a fragmentary plan view of Fig. 9;

Fig. 11 is a fragmentary elevational view, partly 50 in section, of a portion of the electrically actuated mechanism of a receiving machine;

Fig. 12 is a fragmentary plan view of Fig. 11;

Fig. 13 is a view partly in section of the space 55 return switch, as indicated by the line 13—13 of Fig. 3; and

Fig. 14 is a diagrammatic showing of the local circuit for the escapement and space adjusting mechanism.

In printing telegraphs the transmitting machine incorporates a keyboard generally similar to a conventional typewriter. The various keys will, when depressed, operate mechanism to close electrical circuits by which the receiving machines are energized to actuate corresponding mechanism. The transmitter may also include type bars and a platen so that a printed copy is produced at the transmitter as the transmitting keys are actuated. The receiving machines have the printing keys and platens but do not necessarily include a keyboard as they are actuated in accordance with electrical impulses sent from the transmitting machine. As the system of operation of these printing telegraph machines is well known it is thought unnecessary for an adequate disclosure and clear understanding of this invention to reproduce or describe these mechanisms in their entirety, and consequently only those portions of the printing telegraph machines have been illustrated which are thought to be necessary in the description of this invention. Attention is directed at this time to the patents to Edward E. Kleinschmidt 1,565,165, December 8, 1925 and 1,703,152, February 26, 1929 which will be referred to in the description of this invention as illustrative of the sending and receiving machines and the connecting circuit that may be employed. Further, as a considerable portion of the machine structures are common to both the transmitter and receiver it has been thought unnecessary to completely illustrate both transmitting and receiving machines.

Referring now to the drawings, numeral 10 indicates a base upon which is mounted a printing telegraph machine 11 such as may be used at the transmitting station, and comprising a stationary frame 12 having a movable carriage 13. On the base 10 is also a spacing mechanism generally designated 14, having provision for moving the carriage 13 and for adjusting the amount of space movement. The spacing mechanism 14 is here shown as a device separate from the machine 11 but having an operating connection thereto. It is to be understood that this spacing device may be incorporated as an integral part of the machine 11 instead of being separately mounted as illustrated. A carriage 15 forms part of the spacing device 14 and, as shown, is supported at 16 and 17 for free movement on the stationary frame 18. The carriage 13 of the machine 11 is connected to the carriage 15 of the spacing device so that both carriages will move together. The carriage 13 has a platen 20 for support of a paper sheet on which type characters are impressed as the transmitting keys are actuated.

The machine 11 is provided with a keyboard 22 having the usual keys for actuation of the different type bars carrying letters, etc., and for actuating the word space, the carriage shift, etc.

Included in the machine 11 are the usual five selector bars 23 (see Figs. 9 and 10) which, in the case of the transmitting device are displaced in predetermined combinations by key operation to energize the line circuit connecting the transmitting and receiving machines. Similar selector bars 23', as shown in Figs. 11 and 12, are provided on the receiving machine at the receiving station, but the bars 23' are displaced in combinations corresponding to the displacement of the bars 23 by mechanism operated by electrical

impulses in the line circuit connecting the machines for selection and operation of the type bars. The machine at the receiving station is generally similar in construction to the sending machine 11 but does not include manually operable keys nor a copy carrier such as is illustrated in Figs. 1 and 2. The function and operation of the selector bars 23 and 23' are well known in the printing telegraph art, and they consequently are not shown or described in detail here. Reference is here made to the above numbered patents for a complete description of them. The selector bars are, however, shown diagrammatically and reference is made to Fig. 10 which shows a form of transmitting mechanism 24 that is axially actuated by engagement with the selector bars to energize the line circuit 25 in accordance with the selector bar positioning. The line 25 extends to the receiving machine (see Fig. 12) where suitable mechanism is employed to translate the current impulses of the line circuit into movement of the selector bars 23'.

The carriages 13 and 15 are arranged to be moved step by step, as selected keys are struck, and means are provided for controlling the amount of a step in accordance with the number of characters in a line. The carriages are constantly urged toward the left (the right hand margin position) by spring tension which is controlled to effect stepped movements by provision of an advancing device which acts against the tensioned spring. The advancing means as shown, comprises a carriage advancing solenoid 30 (see Fig. 5) and a latching magnet 31 which operate against a ratchet wheel 32, such mechanism taking the place of the escapement ordinarily provided on a typewriter and serving as an escapement in that it gives a predetermined accurate amount of step movement to the ratchet wheel 32. The ratchet wheel has fixed to it a pinion 33, having an operating connection to the carriage 13 through adjustable spacing mechanism affording variable space movement of the carriage. The carriage is advanced one step or one character space movement each time the solenoid 30 is energized. As mentioned it is constantly urged toward the right through provision of a spring. This spring, indicated at 37, is mounted on the frame 18 and carries a spool 39 upon which is wound a ribbon 40 which has connection at 41 to the carriage 15 of the spacing device. As shown, the carriage advancing solenoid includes a coil 45 having a movable armature 46 which at its upper end carries a pawl 47 pivotally connected at 48. The pawl has an end 50 which is adapted to engage successive teeth of the ratchet 32. A laterally extending pawl arm 51 has connected to it a spring 52 which is supported at 53 from the frame 18. This spring serves to hold the solenoid armature in its upper position and is sufficiently tensioned to overcome the tension of the spring 37 and move the carriage against the tension of the spring 37. A stud 55 serves to hold the pawl end in engagement with the ratchet wheel when in the upper position. Each time a space or letter key of the transmitting machine 11 is depressed, a local circuit is completed, as is well known in the art, to energize solenoid 30. Upon energizing the solenoid coil 45 the pawl is withdrawn and, due to the spring 52, is caused to engage the next following ratchet tooth. The pawl also carries a laterally extending arm 56 which, in retracted position, engages the stop 57 so that during the continued energization of the sole-

noid coil after withdrawal of the pawl it is held in a clearance position with respect to the ratchet wheel. Upon deenergizing the coil when a depressed key is released, the first movement 5 of the pawl is into engagement with the ratchet tooth and subsequent movement produces advance of the ratchet wheel by one tooth space to move the carriages 13 and 15 a step to the left.

The escapement latching magnet 31, which 10 holds the ratchet wheel 32 during retraction of the solenoid armature 41, includes a coil 60 and a fixed armature portion 61 which has pivotally connected at 62 a movable armature portion 63. The end of the movable armature carries a pawl 15 64 which is arranged to engage the ratchet teeth. A spring 65 serves to hold this pawl in engaging position except when the coil 60 is energized. During carriage advance, that is, during travel of the carriage from left hand to right hand margin 20 position, as when writing a line, the latching coil 60 is not energized so that upon energization of the solenoid and withdrawal of the pawl 47 the latch magnet pawl 64 prevents return of the ratchet and carriage to the left hand margin 25 position under urge of the spring 37.

A circuit, under control of a contact and operating key, is provided such that at the end of a line both the solenoid 30 and latching magnet 31 may be simultaneously energized to release the 30 ratchet for return of the carriage to the left hand margin position. This circuit as well as the carriage advancing circuit is a local circuit as illustrated diagrammatically in Fig. 14 which shows current supply leads 70 and 71 connected to a 35 suitable source. The lead 70 is shown extending to one end of the coil of the solenoid 30. The lead 71 extends to one side of contact or switch 72 which is operated by any letter or space key of the machine 11. The lead 71 also connects to 40 contact or switch 73 which is adapted to be closed to return the carriage. The opposite side of the switch 72 includes a resistance 74 connecting to the end of the coil of the solenoid 30 opposite the lead 70. The opposite side of the switch 73 45 connects to one end of the coil of the magnet 31 and its opposite end connects at 75 to the circuit of the coil 30. Resistance 74 is provided to give a suitable reduction in current when coil 30 alone is energized by switch 72. The switch 50 73 connects the latching magnet coil and the solenoid coil in series across the line so that upon closure of the switch 73 both coils are energized to permit return of the carriage.

As mentioned above, the operating connection 55 between the carriage advancing device or escapement and the carriage is such that the character space movement may be varied. As mentioned, the movable carriage 15 of the spacing mechanism is supported for free movement 60 on the frame 18, and the movable carriage of the spacing mechanism is attached to the carriage 13 for simultaneous movement. As shown in Fig. 1, the bracket 17 of the carriage 15 has an extending part 83 that is fixedly attached at 84 to the carriage 13. In the illustrated embodiment of the invention the variable spacing mechanism as shown in Fig. 4 comprises a plurality of interconnected gears of varying pitch diameter, each of which has meshing with it a 65 rack which may be selectively attached to the carriage 15 of the spacing device to provide the desired extent of character space. The gears, numbered 90 to 96, are fixedly mounted upon a shaft 97 which is supported for rotation at 98 70 from the spacing mechanism frame 18, and at 99

in a bracket 100' also fixed to the frame 18. The gear 90 stands in constant intermeshing relationship with the escapement pinion 33. The gear racks, numbered from 100 to 106 inclusive, are supported in the carriage 15 so that they 5 are free to slide with respect to the carriage. As shown in Fig. 3 the carriage 15 carries cross members 107 and 108, each of which has spaced slots 109 corresponding in position to the racks, and each carries a supporting pin 110 which engages 10 slots 111 in the racks. The slots 111 are of sufficient length to permit the required free movement of the racks. Each rack terminates in an extending end 112 which is provided with a transversely projecting stud 113 (see Fig. 6). The assembled relationship of the gears and racks is such that when the carriage is in the left hand margin position these studs 113 will stand in axial alignment. The racks are operatively connected 15 to the carriage part through provision of latches 20 which may selectively engage the different studs upon actuation of a control device. As shown, the left hand pin 110 serves also as a supporting pivot for a plurality of latches numbered 120 to 25 126 inclusive which lie closely adjacent their 30 corresponding racks. Each latch is provided with a notch 127 which is positioned with respect to the pivot axis 110 to engage the corresponding rack stud 113 upon lowering the latch when the carriage is in the left hand margin position. 35 These latches are urged downwardly through provision of springs 128 and are controlled in their downward latching movement by a control device indicated generally by the numeral 129 and shown as comprising a plurality of axially spaced cams 40 which are carried upon a shaft 130 rotatably supported at 131 and 132 on the carriage part 15. These cams, numbered 140 to 146 inclusive, are of disk like form and each has a V-shaped notch. The cams are axially spaced on the shaft corresponding to the latching members and the notches have a uniform angular spacing so that but a single latch is engaged at a time. As shown, the latch ends are provided with rollers 147 for free 45 rotation on the periphery of the cams.

The gears 90 to 96 are of related diameters so coordinated that all of them will provide space lengths such as to equally divide into a predetermined line length. That is, the spacings afforded by the different gears are of aliquot fractions of a predetermined line length. The gear relationship is based on what might be termed normal spacing, that is, a spacing corresponding to that of a conventional typewriter which, for example, will produce ten characters to the inch 55 so that a 6" line will contain sixty character spaces. We will assume that in this illustrative example the smallest gear 90 of the several gears is of such pitch diameter as to advance the carriage by $\frac{1}{60}$ " for each movement of the escapement. There will then be ten character spaces for each inch of travel or sixty character spaces in a 6" line. The other gears are of successively increasing diameter and bear predetermined relation to the first gear and to each other which is such that each gear will traverse the carriage for the predetermined line length with one less character space than the next preceding gear. That is, gear 91 will traverse the 6" sixty normal space line with only fifty-nine character spaces and 60 gear 92 do likewise with only fifty-eight character spaces.

This particular example of spacing relationship has been chosen because it is based on a normal spacing corresponding to spacing found 75

in conventional typewriters. In reproducing copy on this machine to justified lines it is first written at normal spacing wherein the lines will be off irregular length due to the fact that but 5 a single space length is afforded. This unjustified copy is then used at the transmitting station as an index in selecting the required length of character space for reproduction of a selected line to justified line length. This original or un 10 justified copy may be prepared on a machine that is capable of writing to normal spacing. The unjustified copy is then placed in a copy carrier on the transmitting machine 11 and is used as a reference in establishing a space length for the 15 transmitting machine, and also for the receiving machine or machines for reproducing the unjustified copy to justified length through provision of control mechanism which is operable to alter the space length in accordance with the 20 indicated unjustified line length.

As shown, the movable carriage 15 of the transmitter is provided with a copy carrier 150 which comprises a frame 151 carried by brackets 152 extending to the carriage part 15, and having 25 supporting bearings 153 for free rotation of a roller 154. The roller has an operating handle 155 by which it may be rotated. The carrier is of such form as to receive the unjustified copy and to support it in view of the transmitting operator when this copy is carried around the roller 154. Suitable clips 157 are provided which are mounted on a cross rail 158 on the carrier. These clips serve to hold the unjustified copy in place against the roller so it may not be un 30 intentionally displaced, and so that it will be held to be readily visible to the operator. A pointer 160 is provided on the transmitting machine as an indicator for reference with the unjustified line ends. This pointer is operatively 35 connected to the control shaft 130, and is arranged to move in coordinated relationship with the movement of that shaft. The pointer 160 terminates at its upper end at a point opposite the carrier roller, and at its lower end is affixed 40 to a cross bar 161 that is mounted for sliding movement on the members 107 and 108 that support the racks. As shown, the bar 161 is slotted as indicated at 162 to receive screws 163 that are held in the supporting members. A spring 164 45 serves to constantly urge this pointer bar to the right at which end it is provided with a roller 165 that engages the peripheral edge of a cam 166. This cam is provided with a series of stepped faces corresponding in number and in 50 angular positioning to the notches of the several cams 140 to 146. As shown, the cam faces stand at progressively increasing distances from the center of rotation of the shaft 130 and bear a relationship to the latch cams such that the cam 55 face of shortest radial length will stand opposite the pointer bar when the cam notch of the cam 140 is aligned for latching engagement of the rack 100 that meshes with the normal spacing gear 90. Further, the difference in elevation of the stepped faces of this cam is the same as normal letter spacing so that as the cam is rotated 60 the pointer will move in stepped amounts corresponding to normal character spacing; the spacing of the unjustified copy. If the control 65 is positioned to afford the normal spacing described above, and the unjustified copy is placed in the carrier so that the end of a sixty space line, the established predetermined line length, stands in registration with the pointer, that line 70 may then be typed on the machine and will cor-

respond in length with the unjustified line as both 5 of these are written to the same spacing. Having established the positioning of the unjustified copy, if a shorter line is then brought into position on the carrier and the indicating pointer is moved into registration with this line end by rotation of the control shaft, there will be a simultaneous and automatic adjustment of the spacing mechanism such that this shorter line will be reproduced to the predetermined line 10 length when it is typed. This is because of the coordination of pointer movement and relationship of the several spacing gears.

The construction just described is that of the transmitting machine of a printing telegraph system which incorporates in addition to the transmitting mechanism the usual type bars and platen of a typewriter so that the operator can see the transmitted subject matter. The arrangement, as described, is such that the transmitted typed matter appears on the platen in justified form. It will be understood however that control mechanism is provided whereby the copy reproduced at the receiving machines will also appear in justified form. As the spacing 25 mechanism in the receiving machines is substantially a duplicate of that just described it is thought that the operation of this device will be apparent without a complete drawing of the receiving machine. The receiving machines, of course, will not include the copy carrier and pointer as this is used only at the transmitter as a reference in typing the subject matter to be transmitted from unjustified copy. Except for this the spacing mechanism of both transmitter and receiver is the same in construction. In the receiving machine actuating bars are substituted for the key bars for actuation of the different type bars in accordance with the movement of the selector bars.

Keys are provided on the transmitting machine to provide for adjustment of the space length of the transmitter and corresponding actuating bars under the control of such keys are provided on each receiving machine whereby justified copy 45 is produced. A typical key for adjusting the spacing mechanism or its return to normal as is illustrated in Figs. 9 and 10, and is shown as comprising a bar 170 which is pivoted at 171 from the frame 12 and has the usual key button 172 50 by which it is depressed. A spring 173 is provided to hold this key in its normal upward position. This key, like the letter keys and other keys of the transmitting machine, stands directly above the selector bars 23 and, like the other 55 keys, there is provision in the selector bars for movement thereof in a predetermined relationship upon depression of these justifying control keys. There are two keys for justifying purposes, one for actuating the space adjusting mechanisms 60 to adjusted position, and an additional one to return the mechanisms to normal position prior to a second adjustment. Referring now to the transmitting mechanism, there is a lug 175 on the key bar 170 that is positioned to close the circuit 65 of a switch 176 upon actuation of the key. The switch 176 is in a local circuit shown in Fig. 14 at the transmitting station, a similar circuit and mechanism being provided for each receiving machine. This circuit includes the coil of a solenoid 180 that serves to advance the justifying spacing mechanism. As shown, the space advancing solenoid 180 comprises a coil 181 having an armature 182 that is held in a downward 70 position through provision of a spring 183. The 75

upper end of the armature carries a pawl 184 pivoted thereto at 185. The pawl has an engaging end 186 which is adapted to engage and advance a ratchet 190 by successive engagement with the ratchet teeth. In unenergized position of the solenoid the pawl 184 is held out of engagement with the ratchet through provision of a lug 191 that engages the solenoid end and swings the pawl end 186 outwardly. Upon energizing the solenoid the spring 192 acts to swing the pawl end inwardly against the ratchet so that upon further upward movement it advances the ratchet by one tooth; being guided at the end of its stroke by the stud 193.

The ratchet 190 is fixed to a splined shaft 195 that extends transversely of the machine and which has slidably mounted upon it a bevel gear 196 rotatably supported in a bracket 197 on the movable carriage 15, and on the corresponding carriage of the receiver. This gear also carries a spline so that it rotates with the shaft 195 although it is axially slideable thereon. The gear 196 meshes with another bevel gear 198 that is fixed to the end of the control shaft 130. The tooth spacing of the ratchet 190 and the relationship of the gears 196 and 198 is such that for each tooth movement of the ratchet 190 the control shaft 130 will be moved angularly an amount sufficient to step from one latch engaging position to the next adjacent latch engaging position. Movement of the control shaft and associated parts from the normal position is resisted by a spring 200 which constantly urges these parts toward normal positioning. Advancing movement by the solenoid 180 is against the tension of this spring. A latching magnet 205 is provided to hold the control in adjusted position against tension of the spring. As shown, the latching magnet comprises a coil 206 having a fixed armature part 207 to which is pivotally attached at 208 a movable armature 209 carrying pawl 210 adapted for engagement with the ratchet teeth and held in engagement by a spring 211.

Each time the key 170 at the transmitting station is depressed it closes the circuit of the switch 176 and completes a circuit from the local supply lines 70 and 71 through the coil of the solenoid 180 to energize the solenoid and advance the spacing mechanism by one step. As mentioned, when deenergized the solenoid pawl 184 stands out of engagement with the ratchet 190. The latching magnet pawl, however, remains in engagement to hold the control in adjusted position. In operating the justifying mechanism the key 170 is depressed the required number of times to move the pointer 160 into registration with an unjustified line end. Each time the key is depressed it moves the space adjusting control by one step, and moves the pointer accordingly. Also, it actuates the selector bars of the transmitter each time so that the proper electrical impulses are transmitted to the receiving machines through the transmitting impulse mechanism 24 of the transmitter which connects through the line 25 to a selecting mechanism of any suitable or well known construction at the receiving machine. This produces similar actuation of the receiving selector bars and operation of the receiving machine space adjustments.

To refer now more particularly to the receiving machine;—type bar actuation may be in accordance with that shown in Kleinschmidt 1,565,165, and the common operating mechanism shown in that patent may be utilized in actuating the carriage advance as well as the space ad-

justing mechanism. As pointed out previously, the receiving machine is provided with actuating bars which, in effect, correspond to the keys of the transmitting machine. Actuating bars are provided for the carriage advance and space adjustment and serve, upon operation, to close the circuits to the various control solenoids and magnets. One of the actuating bars or pull bars is shown in Figs. 11 and 12, and is illustrated as comprising a pivotally mounted bar 225 that is supported at 226 from the frame structure 12 which includes also a support 228 for a switch 229 which corresponds in function to the switch 176 of the transmitting machine. The switch has an arm extension 230 which is tensioned against an insulating member 231 fixed to the pull bar. This pull bar, like the other pull bars of the receiving machine, stands directly above the selector bars 23' of the receiving machine, and will drop into the bar notches when the proper combination of selector bar movement is effected. Upon dropping into the selector bar notches the switch 229 is closed and energizes the space adjusting solenoid corresponding to the solenoid 180 of the transmitter. The pull bar just described has a spring 230 urging it downwardly and has a lug 231 which engages the roller 232 of the rock shaft 233 that is operatively connected to the solenoid 234 that is automatically actuated in a printing telegraph machine subsequent to movement of the selector bars. This solenoid operation is well known in the art, and it is believed that further description is unnecessary. A separate pull bar is provided for return of the space adjustment to normal on the receiving machine just as a separate key is provided on the transmitting machine for this purpose.

Upon completion of a line of writing the carriage is returned to the left hand margin position by depressing a key to close the carriage return switch 73. Subsequently a control key similar to the illustrated key 170, and having a switch 214, is then depressed to close a local circuit and to energize the adjustment latching magnet 205 for release of adjusting mechanism to normal position under urge of the spring 200; a suitable stop being provided for the control shaft 130 in the normal spacing position. This operation takes place at both the receiving and sending stations.

Means are provided whereby spacing adjustment and return of the spacing adjustment to normal position can be accomplished only when the carriage is in the left hand margin position. As shown, a switch 215 is provided in the circuits of the solenoid 180 and latching magnet 205. This switch is normally urged to the open circuit position, and is only closed by movement of the carriage to left hand margin position. As shown, the frame 18 carries a switch box 216 which encloses a stationary contact 217. Enclosed also is a movable contact 218 that is attached to a pivotal arm 219 supported on a pivot axis 220. A spring 221 urges this switch towards the open circuit position and holds it so against the stop 222. The switch arm 219 extends upwardly for engagement by a stud 223 that is fixed to the movable carriage part 15, and is positioned to close this switch only when the carriage is in the left hand margin position. At other times this switch is open so that the circuits of the solenoid 180 and the magnet 205 are inoperative. This switch also is found at both transmitter and receiving machines.

- It is through that it is now apparent that through the practice of this invention it is readily possible to utilize printing telegraph machines for the transmission of copy in justified form.
- 5 And that further, by utilizing telegraph printers in this manner copy is reproduced in such form as to be ready for use in justified lines without the necessity of first recopying it to justified line length. Still further advantages obtain in that 10 the copy may be taken directly from the machine and may be converted, as by a photo-lithographic or photo-engraving process, into a printing plate suitable for use in the production of a news column or a printed page.
- 15 While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a printing telegraph system, a transmitter for selecting type characters and a receiver operated by said transmitter for grouping type characters in space relationship, adjustably variable character spacing means on said receiver, a control circuit connecting the transmitter and receiver, and means operable at the 25 transmitter and effective on the control circuit for adjustably varying the spacing means at the receiver for justifying lines of characters at the receiver.

2. In a printing telegraph system, a transmitter for selecting type characters and a receiver operated by said transmitter for grouping selected type characters, selectively variable character spacing means on said receiver, a control circuit connecting the transmitter and receiver, 35 a contactor in the control circuit at the transmitter, means at the receiver connected to the control circuit for movement by contactor actuation for selectively varying the character spacing means to adjust the length of character space 40 45 movement of said receiver spacing means by amounts differing by one whole character space in a predetermined line length.

3. In a printing telegraph system, a transmitter for selecting type characters and a receiver 50 operated by said transmitter for grouping selected type characters, character spacing means on said receiver, justifying means for varying the extent of character space length of the receiver in predetermined amounts varying from one another by one whole character space in a justified line 55 length, and control means therefor operable at the transmitter comprising a contactor adapted for repeat operation to alter the space length by one whole character space in a justified line 60 length for each successive actuation thereof.

4. In a type character associating device adapted to associate characters in lines of justified length, a transmitter having means for selecting type characters, a receiver controlled by 65 said transmitter for associating the selected characters in spaced relationship, character spacing means on the receiver, means for varying the extent of character space length of the receiver in predetermined amounts varying from 70 one another by one whole character space in the justified line length, and control means therefor operable at the transmitter and comprising a contactor adapted for repeat operation to alter the space length of the receiver by one whole character space in a justified line length for 75

each successive actuation thereof, and means at the transmitter for indicating the required space length.

5. In a type character associating device, a transmitter having means for selecting type characters, a receiver remotely controlled by said transmitter for associating the selected characters in spaced relationship, said receiver having a platen movable between right and left hand margin positions and having spacing means 10 adapted to move said platen by character space steps, a circuit controlling switch at the transmitter, means controlled thereby at the receiver for varying the extent of a character space step, and means controlled by movement of the platen 15 to render said switch ineffective except in one margin position of said platen.

6. In a type character associating device, a transmitter having means for selecting type characters, a receiver remotely controlled by said transmitter for associating the selected characters in spaced relationship, said receiver having a platen movable between right and left hand margin positions and having spacing means 20 adapted to move said platen by character space 25 steps, means comprising a circuit and a controlling switch therefor to vary the extent of character space movement of said platen with respect to a normal space movement, means comprising a second circuit and a controlling switch to return the spacing means to normal spacing, a safety switch controlling the circuits of the space varying and return switch, means operable with said platen to close said safety switch in only one margin position of the platen for closure of 30 said space varying and return switch circuits only in the one margin position.

7. In a printing telegraph system, a transmitter for selecting type characters and a receiver operated by said transmitter for grouping selected type characters, character spacing means on said receiver, means for varying the value of a character space of the receiver with respect to a normal space length in predetermined amounts varying from one another by one whole 40 character space in the justified line length, means urging the space varying means to normal positioning, control means for the space varying means operable at the transmitter and comprising a contactor adapted for repeat operation to alter the space length of the receiver by one whole character space in a justified line 45 length for each successive actuation thereof, holding means engaging said space varying means to maintain the spacing means in adjusted 50 positioning, and a separate contactor at the transmitter adapted upon actuation to disengage the holding means for return of the spacing 55 means to the normal position.

8. In a printing telegraph system, a transmitting typewriting device, a receiving typewriting device, adjustably variable spacing means at the receiving device adjustable for varying the length of character spacing to reproduce unjustified copy to justified line length, a copy carrier at the transmitting device to hold unjustified copy in predetermined positioning, indexing means at the transmitting device registerable with a line end of the unjustified copy as an index of adjustment of the spacing means to reproduce the indicated line 70 to justified length, and electrical means connecting the receiver and transmitter for positioning the adjustably variable spacing means at the receiving device in accordance with the positioning of the indexing means at the transmitting device.

9. In a printing telegraph system, a transmitting typewriting device, a receiving typewriting device, a control circuit connecting the transmitting device and the receiving device, adjustably variable spacing means at the transmitting and receiving devices having connection to the control circuit and adjustable for varying the length of character spacing to reproduce unjustified copy to justified line length, a copy carrier at the transmitting device to hold unjustified copy in predetermined positioning, indexing means at the transmitting device movable into registration with a line end of the unjustified copy as an index of adjustment of the spacing means to reproduce the indicated line to justified length and operably connected to the transmitting device spacing means for movement in coordinated relationship therewith, and means at the transmitting device to energize the control circuit.
10. In a printing telegraph system, a transmitter for selecting type characters and a receiver for grouping the selected characters at predetermined spacing, a control circuit connecting the transmitter and receiver, adjustably variable spacing means at the receiver having connection to the control circuit and adjustable for varying the length of character spacing to reproduce unjustified copy to lines of justified length, a copy carrier at the transmitter to hold unjustified copy in predetermined positioning, indicating means at the transmitter movable into registration with a line end of the unjustified copy as an index of adjustment of the spacing means to reproduce the indicated line to justified length, and means in the control circuit at the transmitter having coordinated actuation with the movement of the indicating means for adjustment of the receiver spacing means.
11. In a printing telegraph system, a transmitter for selecting type characters and a receiver for grouping the selected characters at predetermined spacing, a control circuit connecting the transmitter and receiver, adjustably variable spacing means at the receiver having connection to the control circuit and adjustable in steps of one character space in the justified line length for varying the length of character spacing to reproduce unjustified copy to lines of justified length, a copy carrier at the transmitter to hold unjustified copy in predetermined positioning, indicating means at the transmitter movable in steps of one character space of the unjustified copy into registration with a line end of the unjustified copy as an index of adjustment of the spacing means to reproduce the indicated line to justified length, and means in the control circuit at the transmitter having coordinated actuation with movement of the indicating means for adjustment of the receiver spacing means.
12. In a printing telegraph system, a transmitter for selecting type characters and a receiver for grouping the selected characters at predetermined spacing, a control circuit connecting the transmitter and receiver, adjustably variable spacing means at the receiver having connection to the control circuit and adjustable for varying the length of character spacing to reproduce unjustified copy to lines of justified length, a copy carrier at the transmitter to hold unjustified copy in predetermined positioning, indicating means at the transmitter movable into registration with a line end of the unjustified copy as an index of adjustment of the spacing means to reproduce the indicated line to justified length, and keying means in the control circuit at the transmitter for concomitantly moving the indicating means and energizing the control circuit.
13. In a printing telegraph system, a transmitter for selecting type characters and a receiver for grouping the selected characters at predetermined spacing, a control circuit connecting the transmitter and receiver, adjustably variable spacing means at the receiver for varying the length of character spacing to reproduce unjustified copy to justified length, a solenoid operatively connected to the control circuit for actuation of the adjustable spacing means in accordance with energization of the control circuit, a copy carrier at the transmitter to hold unjustified copy in predetermined positioning, indicating means at the transmitter movable into registration with a line end of the unjustified copy as an index of adjustment of the spacing means to reproduce the indicated line to justified length, a solenoid operatively connected to the control circuit for actuation of the indicating means in accordance with energization of the control circuit, and means to energize the control circuit.
14. In a printing telegraph system, a transmitter for selecting type characters and a receiver for grouping the selected characters at predetermined spacing, a control circuit connecting the transmitter and receiver, adjustably variable spacing means at the receiver for varying the length of character spacing to reproduce unjustified copy to justified length and adjustable from a normal position in amounts differing by one whole character space in the justified line length, a solenoid operatively connected to the control circuit for actuation of the adjustable spacing means in accordance with energization of the control circuit, a copy carrier at the transmitter to hold unjustified copy in predetermined positioning, indicating means at the transmitter movable into registration with a line end of the unjustified copy as an index of adjustment of the spacing means to reproduce the indicated line to justified length, a solenoid operatively connected to the control circuit for actuation of the indicating means in accordance with energization of the control circuit, and means to energize the control circuit.
15. In a printing telegraph system, a transmitter for selecting type characters and a receiver for grouping the selected characters at predetermined spacing, a control circuit connecting the transmitter and receiver, adjustably variable spacing means at the receiver for varying the length of character spacing to reproduce unjustified copy to justified length and adjustable from a normal position in amounts differing by one whole character space in the justified line length, means urging the adjusting means to normal position, a solenoid operatively connected to the control circuit for actuation of the adjusting means in accordance with energization of the control circuit, a copy carrier at the transmitter to hold unjustified copy in predetermined positioning, indicating means at the transmitter movable into registration with a line end of the unjustified copy as an index of adjustment of the spacing means to reproduce the indicated line to justified length and movable from a normal position corresponding to the justified line length in steps of one space length, means urging the indicating means to normal position, a solenoid operatively connected to the control circuit for actuation of the indicating means in accordance with energization of the control circuit, means to energize the solenoid control circuit, a second

control circuit operable to return the adjusting means and indicating means to normal position, and means to energize the second control circuit.

16. In a printing telegraph system comprising a transmitter for selecting type characters and a receiver for grouping the selected characters at predetermined spacing, a control circuit connecting the transmitter and receiver, adjustably variable spacing means at the receiver 5 mounted for reciprocatory movement thereon and adjustable for varying the length of character spacing to reproduce unjustified copy to lines of justified length, adjusting means for the spacing means comprising a rotatable splined 10 shaft extending in the direction of movement of the spacing means, shaft moving means operatively connected to the shaft for controlling rotational movement thereof and connected to the control circuit, means connected to the spacing 15 means and slidably mounted in driving engage-

ment on the splined shaft, and means operable at the transmitter and connected to the control circuit for actuation of the space adjusting means.

17. In a printing telegraph system, a transmitter for selecting type characters and a receiver for grouping the selected characters at predetermined spacing, variable spacing means at the receiver comprising a plurality of selectively engageable relatively fixed spacing members of differing space length characteristics, a control 10 circuit connecting the transmitter and receiver, space adjusting means at the receiver connected to the control circuit and operable in accordance with energization thereof for selective engagement of a desired spacing member, and means 15 operable at the transmitter and effective on the control circuit for actuation of the space adjusting means. 5

EDWARD C. WELLS. 20
